UNITED STATES PATENT OFFICE.

OSCAR GORDON RANKINE, OF BOSTON, MASSACHUSETTS.

DESIGN FOR A BOTTLE.

SPECIFICATION forming part of Design No. 25,023, dated December 31, 1895.

Application filed May 27, 1895. Serial No. 550,870. Term of patent 7 years.

To all whom it may concern:

Be it known that I, OSCAR GORDON RANKINE, a citizen of the United States, residing in Boston, in the county of Suffolk and State of Massachusetts, have invented and produced a new and original Design for Bottles, of which the following is a specification, reference being had to the accompanying drawings, forming a part thereof.

In the drawings, Figure 1 is a perspective view showing my design; and Fig. 2 is a horizontal section of the same, these two views being deemed necessary to fully illustrate my design.

My design is embodied in a bottle having two of its vertical sides narrow and deeply concaved, as indicated at CC, and having one

of its wide faces flat and the other or opposite face provided with a panel P, as shown. The junction at the neck of the bottle with the body has a bead D, which is a distinguishing feature of my design. The design as a whole is shown in Fig. 1 of the drawings.

I claim—

The design for a bottle substantially as herein shown and described.

In testimony whereof I have signed my name to this specification, in the presence of two subscribing witnesses, on this 24th day of May, A. D. 1895.

O. GORDON RANKINE.

Witnesses:

FRANK G. PARKER,
WM. P. PERRY.
